UNITED STATES PATENT OFFICE.

EPHRAIM G. PEYTON, OF THE UNITED STATES ARMY, WASHINGTON, DISTRICT OF COLUMBIA.

CIRCUIT CLOSER.

Application filed September 30, 1925. Serial No. 59,630.

This invention relates to electrical apparatus, particularly to circuit closers, and has for its object the provision of a novel device particularly designed for use beneath a rug, carpet, mat or the like and operable to complete a circuit through a call bell, or like signal and to produce a light or reduce the intensity of a light of temporary duration.

10 An important object is the provision of a device of this character of such construction that there will be no metallic parts, buttons or other similar elements in contact with the rug or other floor covering and tending to 15 wear the same unduly.

Another object is to provide a device of this character which is substantially flat so as not to produce any noticeable hump or rise in the floor covering.

20 Another object is to provide a device of this character, which is movable and easily adjustable to a location convenient to the operator.

Another object is to provide a device of 25 this character for producing a light of temporary duration or of temporarily reducing the intensity of a light, for instance to enable the driver of a motor drawn vehicle to operate a spot light or to dim his lights, without removing a hand from the steering wheel.

An additional object is the provision of a circuit closer of this character which will be simple and inexpensive to manufacture, easy to use, efficient and durable in service, 35 a general improvement in the art, and tending to promote safety in the operation of motor drawn vehicles.

With the above and other objects and advantages in view, the invention consists in 40 the details of construction and arrangement of parts to be hereinafter more fully described and claimed, and illustrated in the accompanying drawing in which:

Figure 1 is a view showing the device located beneath a rug or the like,

Figure 2 is a top plan view of the device on a larger scale,

Figure 3 is a bottom plan view thereof,

Figure 4 is a section taken on the line 50 4-4 of Figure 2, and

Figure 5 is a detail perspective view of the contact carrying member.

Referring more particularly to the drawings I have shown the device as comprising 55 a flat base member 10 of flexible material

such as leather, rubber or the like, the exact material being a matter of choice though it should have insulating qualities. Though it is not essential, this base is shown as of elongated form with one end portion 11 60 widened and formed with an arcuate slit 12 defining a flexible tongue 13. At spaced points the base is formed with transverse slits 14 defining tongues 15 therebetween through which or beneath which may be 65 threaded the current carrying wires 16 which will thus be anchored to the base.

Mounted on the underside of the base at the tongue portion 13 thereof is a supporting block or plate 17 of rigid but insulating material upon which is secured a metallic strip 18 which constitutes the stationary contact, one end of this strip being held by a screw 19 and the other being formed with a tongue or extension 20 bent about the free 75 end of the member 17. Likewise secured upon the member 17 as by a screw 21 is a spring metal strip 22 constituting the movable contact. This strip 22 is normally spaced from the strip 18 and has its free 80 end formed with angularly extending lugs 23 which are passed through the tongue portion 13 of the base and clinched. By this means the member 17 is anchored with respect to the base. The tongue portion 13 is 85 formed with holes 24 permitting access to the screws 19 and 21, these latter constituting terminal means to which the conducting wires are connected.

In use, the device is placed beneath a rug, carpet, mat or other floor or table covering indicated at A. As the device is substantially flat there will be no perceptible hump, bulge or rise to disfigure the appearance. Whenever it is desired to close the circuit 95 through a call bell light or other device with which the circuit closer may be associated, it is merely necessary to apply pressure to the rug or other covering at a point above or near the resilient tongue 13 to effect downward movement thereof and consequent engagement of the movable contact 22 with the stationary contact 18. Obviously the device is easy to operate and it is believed that the construction and advantages will be readily apparent to one skilled in the art without further explanation.

While I have shown and described a preferred embodiment of the invention, it should be understood that I reserve the right 110

to make such changes in the form, construction and arrangement of parts as will not depart from the spirit of the invention or the scope of the subjoined claims.

5 Having thus described the invention, I claim:

1. A circuit closer of the character described comprising a flat member of insulating material having one end portion 10 formed with a partially circular cut to define a flexible tongue, a flat supporting member of insulating material secured beneath said member, a stationary metal contact strip mounted on said flat supporting member, a 15 spring contact member secured upon said flat supporting member and normally arranged in spaced relation to said stationary contact, said spring contact having a head portion formed with penetrating elements 20 engaged through said resilient tongue.

2. A circuit closer of the character de-

scribed comprising a flat member of insulating material having one end portion 25 formed with a partially circular cut to define a flexible tongue, a flat supporting member of insulating material secured beneath said member, a stationary metal contact strip mounted on said flat supporting member, a 30 spring contact member secured upon said flat supporting member and normally arranged in spaced relation to said stationary contact, said spring contact having a head portion formed with penetrating elements engaged through said resilient tongue, said first named member being provided with a 35 plurality of spaced transverse slits, and a conducting cable threaded through said slits and embodying two conducting wires connected with said respective contact strips.

In testimony whereof I affix my signature.

EPHRAIM G. PEYTON.
